SELF-ADJUSTING WRENCH FOR NUTS OR
LIKE POLYGONAL OBJECTSMogens Fin Stellinger, Copenhagen, Denmark,
assignor to The Cromna Company, Copenhagen, Denmark, a firmApplication June 10, 1949, Serial No. 98,188
In Great Britain December 16, 1948

3 Claims. (Cl. 81—91)

1

This invention relates to wrenches and is, more specifically, concerned with wrenches of the type disclosed in the co-pending patent application Serial No. 786,289 by S. O. Mortensen. The wrench in accordance with the said patent application comprises a pair of opposed jaws of which one is rigidly connected with the shank or handle of the wrench, whilst the other jaw is substantially hook-shaped and pivotally connected with the handle in such a manner that the jaws are squeezed against an object engaged between them when the handle is actuated to turn such object, one of the jaws being provided with an approximately semi-cylindrical jaw member pivotally mounted in an arcuate recess in the jaw in question in such a manner that the flat face of such member constitutes the gripping face of said jaw.

As a result of experiments made, it has been found that the best construction is that in which the semi-cylindrical jaw member is mounted in the handle of the wrench. This construction, however, involves certain practical problems the solution of which constitutes the object of the present invention.

Another object is to provide such construction of the wrench in question as to ensure that the gripping face of the semi-cylindrical jaw member will always automatically facially engage a nut or the like to be turned by means of the wrench.

Still another object is to generally improve the wrench disclosed in the aforesaid patent application.

The invention will now be described in detail with reference to the accompanying drawing in which

Fig. 1 is a side-view of a wrench in accordance with the invention,

Fig. 2 is a section taken along the line II—II in Fig. 1, and

Fig. 3 illustrates the geometrical determination of the wrench.

In the drawing, 1 is the handle of the wrench, 2 a bearing for an arcuately sliding jaw 9, the bearing being integral with the handle, and 5 a pivotable hook-shaped jaw which, by means of a pin 4 is hingedly connected with the handle 1, which latter is formed with a recess 16 engaged by an approximately circular web 15 on the jaw 5. A coil spring 17 is provided in the recess 16 and acts to urge the pivotable jaw 5 towards the arcuately sliding jaw 9. The latter is formed by an approximately semi-cylindrical member and is mounted for pivoting movement in its bearing

2

2 in such a manner that its flat face 3 constitutes the gripping face of the jaw. The gripping face of the pivotable jaw is denoted by 6 and this jaw is furthermore provided with a face 7 constituting an angle of 120° with the gripping face 6 and acting as an abutment for a nut 8 engaged in the wrench.

The jaw 9 is retained in its bearing by means of a dove-tail groove 11 formed on the circumferential portion of the jaw and engaged by a corresponding feather 10 provided in the bearing 2. In order to limit rotation of the jaw 9 relative to the bearing 2 a set screw 12 is inserted from the recess 16 to engage a smaller groove 13, which is formed in the bottom of the dove-tail groove 11 and extends over a certain angle only of the circumferential face of the jaw 9. The length of the groove 13 is such as to permit the jaw to adjust itself freely to engage the side face of any nut of a size within the range of span of the wrench.

It will be appreciated that, if the gripping face 3 of the jaw 9 shall apply itself automatically to the side face of the nut 8 when the handle 1 is actuated in the direction of the arrow C to squeeze the jaws of the wrench together about the nut, the lower face of the nut must, in the position defined by the faces 6 and 7, engage the gripping face 3 so as to be intersected by a plane of symmetry 14 perpendicular to said lower face and containing the pivot axis of the jaw 9, and this requirement must be fulfilled with any size of nuts to which the wrench is intended to be applied.

35 It will equally be appreciated that another requirement to be fulfilled in order to ensure effective operation of the wrench is that a line 20 drawn from the axis of the pin 4 to the corner 21 between the faces 6 and 7 is as nearly as possible at right angles to the gripping face 6, because the force with which the wrench urges the nut to rotate will extend in the direction of said line and, therefore, will have a considerable component in the direction of the gripping face 6 if the aforesaid angle is substantially above 90°, whereby the gripping face 6 may be urged to slip upon the nut 8 instead of engaging the same firmly. The ideal would be if the angle between the face 6 and the line 20 were 90°, but this is impracticable and is furthermore practically incompatible with the aforesaid requirement of the engagement between the nut 8 and the gripping face 3, as will become apparent from the following.

55 Supposing that the aforesaid angle were 90°,

3

then the axis of the pin 4 would be situated upon a line 20', e. g. at the point 4'. This would result, when turning the jaw 5 through a definite angle to vary the span of the wrench, in only a very small change of the distance between the faces 3 and 6, and in a relatively great lateral displacement of the nut 8 with respect to the line 14. If under these conditions the requirement is maintained that the nut must engage the face 3 on either side of the line 14, the wrench would afford a very small range of span. With a definite range of span a reduction of the lateral displacement of the nut relative to the line 14 can only be attained by reducing the distance A between the axis of the jaw 9 and the axis of the pin 4. This distance must, however, always be greater than the sum of the radius of the web 15 and the radius of the arcuate recess forming the bearing for the jaw 9. These radii are both determined by practical requirements and with a view to the necessary strength of the wrench. The present invention, however, affords the possibility of substantially reducing the distance A because, contrary to the construction disclosed in the aforesaid copending application, the dovetail groove 11 is formed in the jaw 9 whilst the feather 10 is formed in the bearing 2. Hereby the distance A can be reduced by two times the depth of the groove 11 without reducing the wall-thickness between the recess 16 and the arcuate recess receiving the jaw 9.

The problem to be solved thus resides in balancing the various requirements, which are partly inconsistent with each other, against each other in such a manner that a satisfactory result is obtained. The requirements are, briefly recapitulated, as follows:

1. The wrench must possess a reasonable range of span.

2. A nut of any size within the range of span of the wrench must, when engaged in the wrench, make contact with the gripping face of the jaw 9 on both sides of the pivot axis thereof.

3. The angle between the face 6 and the line 20 must be as near as is possible to 90°.

Practical experiments have shown that these requirements can all be reasonably fulfilled when the ratio between the sizes of the largest and the smallest nut to which the wrench is applicable is about 1½:1 and the ratio between the distance A and the distance between opposed faces of the largest nut does not exceed about 1½:1. It should be noted that, when determining the range of span of the wrench, a minor allowance should be made for enabling the wrench to span the largest nut at diametrically opposed corners thereof, in order to enable it to operate like a ratchet wrench. This implies that the ratio between the largest and the smallest span of the wrench is not the same as the ratio between the sizes of the largest and the smallest nut, viz. 1½:1 approximately, but as far as hexagonal nuts are concerned, approximately $\sqrt{3}:1$ or about 1¾:1. The maximum ratio between the measure A and the largest span of the wrench should accordingly be about 1½:3/2 $\sqrt{3}$ =¾ $\sqrt{3}:1$ or approximately 1.3:1.

If under these conditions the smallest permissible distance between the axis of the jaw 9 and the nearest edge of the nut engaging the gripping face 3 is selected, the wrench is geometrically defined. The geometrical determination of the wrench is illustrated in Figure 3.

This figure only shows such parts of the wrench as are of importance to the geometrical deter-

mination thereof. The principle of effecting the construction may briefly be explained as follows:

The nut 8 is supposed to be situated upon the gripping face 3 of the jaw 9 in the position which is to be assumed when the nut is engaged in the wrench, i. e. when the faces 6 and 7 engage corresponding faces of the nut. Assuming that the nut is of the smallest size to which the wrench is applicable, the nut will have its centre at a certain distance to the left of the line 14 in such a manner that the distance D1 from the line 14 to the lower right corner of the nut 8 is the smallest permissible. The nut is now supposed to increase in size, whilst the cradle 9 is held immovable. When hereby the nut is caused to constantly engage the faces 6 and 7 of the jaw 5, it will be laterally displaced towards the right at the same time as the axis of the pin 4 will be displaced along a circle or arc 21 having its center on the axis of the cradle 9 and a radius equal to A. When the nut has attained its maximum size, which is denoted by 8', the face 6 will have assumed the position 6' and the distance between the line 14 and the lower left corner of the nut 8' will be D2. The distances D1 and D2 may theoretically be freely selected, but practically they are selected in such a manner as to be approximately equal and just enough to ensure the desired automatic adjustment of the jaw 9.

The arc of the circle 21 through which the axis of the pin 4 is displaced, is now determined in the following manner.

The face 6 remaining parallel to itself during the whole movement, the jaw 5 will be displaced in such a manner that all points thereof are displaced parallelly through equal distances. The extent and direction of this displacement are determined by the length L of a line drawn from the upper right corner of the nut 8 to the upper right corner of the nut 8'. Thus this length of line indicates the length and direction of a chord to the arc of the circle 21, through which the axis of the pin 4 is displaced. Therefore, a line 22 is drawn through the point of intersection between the line 14 and the gripping face of the jaw 9 at right angles to the extension of the line L, and subsequently lines 23 and 24 are drawn on either side of the lines 22 at a distance of L/2 therefrom. The points of intersection 4a and 4b between the lines 23 and 24, respectively, and the circle 21 define the arc along which the axis of the pin 4 is displaced when the size of the nut engaged in the wrench varies from minimum to maximum. A line 25 drawn from the point 4a at right angles to the face 6 represents the distance between this face and the axis of the pin 4, whilst the line 20 from the point 4a to the upper right corner of the nut 8 indicates the angle between the face 6 and the direction of the force with which the pivotable jaw acts upon the nut.

The magnitude of the distance A is determined empirically in such a manner as to not exceed 1½ times the measure B over opposed faces of the nut 8' and this measure should in its turn be about 1½ times the corresponding measure b of the nut 8.

As hereinbefore stated, allowance should be made for permitting the wrench to span diametrically opposed edges of the nut 8'. This allowance is determined in the following manner:

An arc 26 having its center in the lower right corner of the nut 8' is drawn from the upper left corner of the nut, and a tangent 6'' to this arc is drawn parallel to the line 6. Subsequently

the point 4c of the circle 21 whose distance from the line 6'' is equal to the length of the line 25, is marked upon the circle, and the angle α of the arc 4a—4c is then the angle through which the jaw 5 must be capable of moving relative to the handle 1. This angular movement is defined by abutments 27 and 28 on the handle of the wrench (Fig. 1). These abutments thus prevent the wrench from being used with nuts to which it is not intended to be applied.

I claim:

1. A wrench comprising a handle, an arcuately slideable jaw associated with said handle, a substantially hook-shaped jaw pivotably connected with said handle and having a workpiece-engaging portion which forms an angular notch, said portion including a substantially straight gripping face confronting said arcuately slideable jaw, an arcuate recess in said handle, a substantially semi-cylindrical member forming said arcuately slideable jaw and having a substantially straight edge face and being mounted in said arcuate recess for free arcuately sliding movement around an axis lying substantially in said straight edge face so as to be positioned, by engaging one parallel side of said workpiece, with its straight edge face parallel to said gripping face of said hook-shaped jaw when the latter engages an opposite parallel side of said workpiece, and means on said hook-shaped jaw and handle for limiting pivotal movement therebetween, so that any polygonal parallel-sided workpieces, between maximum and minimum sizes to be en-

gaged in the wrench, will have said one parallel side engaging said straight edge face on both sides of said axis, when said workpiece abuts an interior corner of said angular notch.

- 5 2. A wrench as in claim 1 in which said semi-cylindrical jaw member has an undercut circumferential groove engaged by a corresponding feather in said arcuate recess to retain said jaw member therein.
- 10 3. A wrench as in claim 1 in which said means for limiting pivotal movement between said hook-shaped jaw and said handle are such as to insure a ratio between the largest and the smallest span of the wrench of approximately $\sqrt{3}:1$ and
- 15 15 a ratio between the distance from the axis of said semi-cylindrical arcuately sliding jaw to the pivot axis of said hook-shaped jaw, and said largest span, not exceeding about $\frac{3}{4}\sqrt{3}:1$.
